DRAFTING LEAD POINT SHAPER

Ewalt H. Rocks, Racine, Wis.

Application January 25, 1950, Serial No. 140,467

5 Claims. (Cl. 120—96)

1

The present invention relates generally to improvements in the art of precision grinding, and relates more specifically to improvements in the construction and operation of mechanism for shaping the end portions of thin and relatively brittle elongated cylindrical elements such as drafting leads confined within a holder or handle.

The primary object of my invention is to provide an improved lead point shaper which is simple and compact in construction, and which also functions with utmost precision to produce points of any predetermined shape or contour.

Various types of so-called pencil sharpeners for renewing broken or worn pencil points with the aid of rotary cutters and abrasive wheels have heretofore been utilized for many years, but none of these mechanisms is adapted to produce lead points of desired shapes with any degree of accuracy such as required for different kinds of drafting and lettering. While it has previously been proposed to sharpen ordinary wooden pencils with the aid of a gear driven rotatable abrasive disk cooperable with a rotary pencil guide disposed tangent to the disk, and wherein the disk was axially movable to grind off more or less of the wood and lead, this prior sharpener was not operable to precisely reproduce specific styles or shapes of lead points adapted for particular uses, and therefore never became popular for drafting room and illustrating services.

It is therefore an important object of my present invention to provide a pencil lead point sharpener especially adapted for use by draftsmen, illustrators, and artists, and which may be preset to accurately reproduce points of any desired shape, contour, or thickness.

Another important object of this invention is to provide an improved motor driven drafting lead pointer which is conveniently operable to quickly and effectively shape new lead points or to restore worn points to any predetermined condition especially adapted for the duty for which they are intended.

A further important object of the invention is to provide an improved lead point shaping unit which is conveniently manipulable to produce points of definite pre-selected contour, which is motor driven to rapidly perform its intended function, and which may be readily mounted in any desired position and locality.

Still another object of my invention is to provide a precision lead point shaping device which is highly dependable in operation, all parts of which are readily accessible for inspection and

2

cleaning, and which may be manufactured and sold at moderate cost.

These and other objects and advantages of the invention will be apparent from the following detailed description.

A clear conception of the features constituting my present improvement, and of the construction and operation of a typical pencil lead point shaping unit embodying the invention, may be had by referring to the drawing accompanying and forming a part of this specification wherein like reference characters designate the same or similar parts in the various views.

Fig. 1 is a top view of a motor driven pencil point shaper showing the location of the motor within the casing of the unit in dotted lines;

Fig. 2 is an end view of the same unit looking toward the pencil applying end, and showing the devices mounted upon a support;

Fig. 3 is a central longitudinal section through the same assemblage, but showing the motor in elevation;

Fig. 4 is a fragmentary section similar to that of Fig. 3 but showing a modified pencil and lead guide; and

Fig. 5 is a view showing three typical considerably enlarged point shapes which may be produced with the improved unit.

The important feature of the present invention is the provision of simple and effective means for enabling accurate production of various definite lead point shapes, and of effecting precise reproduction of any selected point thickness or contour by draftsmen or others having a favorite type of point which they prefer to utilize for certain classes of work.

Referring to the drawing, the improved drafting lead point shaping unit shown therein comprises in general a main housing or casing consisting of a medial frame section 8 and two oppositely disposed cup-shaped covers 9, 10 coacting with the central section 8; a rotor 11 rotatably confined within the cover 9 and having an abrasive side surface 12 disposed approximately perpendicular to the rotor axis; an electric motor 14 secured to one side of the frame section 8 within the cover 10 and having a shaft 15 drivingly connected to the rotor 11 by means of a threaded fitting 16 and a clamping nut 17; a pencil and lead guide 18 mounted upon the opposite side of the frame section 8 and being formed to rotatably confine the pencil and to direct the lead points 20 radially toward the rotor axis and at a slight inclination relative to the abrasive rotor surface 12; a micrometer ad-

justing member 21 having screw threads 22 co-acting with an internally threaded tubular flange 23 formed on the cover 10 and engaging one end of the shaft 15 to move this shaft in one direction; and a leaf spring 24 secured to the frame section 8 and cooperating with the fitting 16 and with the opposite end of the shaft 15 to constantly urge the latter toward the member 21.

The frame section 8 may be formed of any durable metal and has an outwardly projecting integral boss 26 screw threaded for the reception of a stud 27, and a clamping jaw 28 and wing nut 29 may be caused to cooperate with the stud 27 in order to firmly mount the unit upon a support 30 as shown in Fig. 2. The mid-section 8 of the casing provides a partition wall 32 spanning the casing interior, and the motor shaft 15 extends through this wall 32 and is preferably provided with a flexible packing 33 at the point of penetration of the partition so as to prevent dust from escaping from the grinding chamber into the motor confining chamber of the housing. The frame wall 32 also has a large lateral projection 35 formed integral therewith and extending into the cover 9 and to which the pencil and lead guide 19 is adjustably attached by a retaining screw 36 as depicted in Figs. 2 and 3, and the leaf spring 24 may also be secured to this rigid projection 35 by means of another screw 37. The partition wall 32 is furthermore provided with integral bosses 38, 39 projecting from the opposite sides thereof and each of these bosses 38, 39 is provided with a screw threaded socket.

The two cup-shaped covers 9, 10 may be formed of sheet metal with the aid of the same dies, and the brims of these covers are formed to snugly coact with peripheral recesses 41 of the frame section 8 as illustrated in Fig. 3. The abrasive rotor cover 9 has an opening 42 therein adapted to be hooked over the outer end of the normally fixed guide 19, and this cover may be detachably clamped to the frame bosses 38 by means of wing screws 43 so as to seal the grinding zone while still permitting convenient removal of dust produced during normal operation of the unit. The motor cover 10 is also firmly but detachably secured to the frame bosses 39 by means of studs 44 and nuts 45 coacting therewith, and besides providing a mounting for the rotor shaft adjusting member 21, this cover 10 supports a push button switch 46 for controlling the operation of the motor 14 and is also provided with a conductor bushing 47 for the electric wires 48 which supply current to the motor 14 through the switch 46.

The electric motor 14 which is firmly secured to the frame section 8 by means of studs and nuts 50, may be of any suitable construction, either alternating or direct current, and may be placed in operation to rotate the shaft 15 by pressing the button of the switch 46 but will stop quickly when this button is released by virtue of the end pressure exerted upon this shaft 15 by the leaf spring 24. The fitting 16 is drivingly connected to the motor shaft 15 by a screw 51, and the rotor 11 may be either an abrasive cutting wheel or may merely have abrasive opposite side cutting surfaces 12 so that this rotor 11 may be reversibly clamped to the fitting 16 with the aid of the clamping nut 17 and a lock washer.

The specific and accurate formation or shape of the rotor side surfaces 12 is an important feature of the present invention, and as shown in Fig. 3, one side surface of the rotor 11

is substantially plane while the opposite side is provided with an annular fillet having rather abrupt concave curvature near the rotor axis and with a gradually slightly tapered annular surface extending outwardly from near the abrupt curvature. The plane side surface of the rotor 11 may be utilized to produce truly conical lead points 20 or points having flat opposed surfaces, while the other side surface 12 may be used to form relatively blunt tipped points 20 preferably having tapered portions merging with cylindrical portions directly adjoining the rounded tips, as illustrated, and the diameters of these points may be positively predetermined and varied by setting the rotor 11 nearer to or further from the inclined pencil and lead guide 19 while the point shape may be varied by changing the contour of the rotor side surfaces.

The micrometer adjustment for setting the rotor 11 in any preselected position relative to the guide 19 and which consists primarily of the member 21 having screw thread coaction with the annular flange 22 of the casing cover 10, is also an important feature of my invention. The threaded member 21 is adjustable to move the shaft 15 and the rotor 11 axially toward the guide 19, by means of an oscillatory arm 52 one end of which is secured to the member 21 by a nut 53 and the opposite end of which projects laterally over the cover 10 and acts as a pointer cooperating with a series of markings 54 applied to the adjacent outer surface of this cover, as shown in Fig. 1. A relatively stiff helical compression spring 53 surrounds the member 21 and presses against the cover 10 and lever arm 52 so as to hold this arm in any desired position of adjustment, while still permitting convenient swinging of the arm to vary the diameter of the points 20 which are to be formed, and the relatively stiff leaf spring 24 coacting with the fitting 16 serves to move the rotor 11 and the shaft 15 axially away from the guide 19 and to maintain the end of the shaft in snug engagement with the inner end of the member 21 at all times.

While the guide 19 which snugly but rotatably confines the pencil lead holder 57 and the lead 20, and the bottom of which is engageable with the inner end of the holder 57 to arrest the inward advancement thereof is shown in Fig. 3 as being merely axially adjustable in order to produce lead points of any predetermined length, this guide may also be made swingably adjustable to further vary the shapes of the points produced, as shown in Fig. 4. Here the guide 19' is provided with a flat side surface 58, and in addition to the main clamping screw 36 coacting with this surface 58 an auxiliary retaining screw 59 is provided. By maintaining the screw 36 in clamping position and temporarily loosening the screw 59, the guide 19' may be swung slightly in either direction about the main screw 36 as a pivot, and by likewise loosening both screws 36, 59 the guide 19' may be axially adjusted. This modified structure therefore provides an extra means for varying the point shape or contour, in addition to the formation of the rotor side surface 12; but in either case the bottom of the guide provides an abutment for positively arresting the inward movement of the holder 57 and thus always insures the production of lead points of definite length.

During normal use of the improved point shaping unit, it should first be mounted upon a suitable support 30 as shown in Fig. 2 and the plug 60 should be applied to source of electric current.

The lever arm 52 should then be set to cooperate with the marking 54 corresponding to the type of point which it is desired to produce. The pencil or holder 57 may then be inserted within the guide 19 and the lead 20 may be caused to lightly contact the effective rotor side surface 12 whereupon the switch 46 may be operated to start the motor 14 and to thereby rotate the shaft 15 and revolve the rotor 11. Then by gradually urging the lead holder 57 forwardly until its end is arrested by the guide bottom as in Fig. 3, and by simultaneously rotating it within the guide 19, a point 20 of the desired shape, length and diameter will be quickly and accurately produced.

The opposite abrasive side surfaces 12 of the rotor 11 may be formed with different contours so that by reversing this rotor 11 upon the fitting 16 points 20 of different contours may be produced, and by adjusting the arm 52 so as to point to different markings 54 points of different diameters may also be produced. Additional rotors 11 having considerable variation in the shape of the abrasive or cutting surfaces 12 may be provided, and considerable change in the angularity of the guide 19 may also be effected, in order to produce points 20 of any desired contour. The abrasive surfaces 12 may in fact be far more steeply inclined relative to the rotor axis and may even be peripheral rotor surfaces, while the axis of the guide 19 may also be disposed substantially parallel to the rotor axis. A few typical point shapes 20, 20', 20'' are illustrated in Fig. 5 but obviously many others are possible, and the motor 14 may be stopped by merely releasing the switch 46.

After the unit has been in use for some time, the cover 9 should be removed by releasing the screws 43 in order to effect removal of accumulated lead dust; and the cover 10 should also be occasionally removed by releasing the nuts 45 so that the motor bearings may be lubricated. Since the member 21 merely contacts the shaft 15 and is not attached thereto, such removal of the cover 10 is readily possible. When an adjustment of the rotor 11 in order to decrease the point diameter is made, the micrometer member 21 pushes the rotor 11 and the shaft 15 toward the guide 19 by slight increments precisely the desired amount; but when the setting is such as to enlarge the point diameter, then the leaf spring 24 functions to push the rotor and shaft in opposite direction.

From the foregoing detailed description of the construction and operation of a typical lead shaping unit embodying the present invention, it should be apparent that I have in fact provided a simple and compact mechanism for producing lead points 20, 20', 20'' of diverse accurately performed contours with utmost precision. By locating the pointer end of the adjusting arm 52 closely adjacent to the switch 46, manipulation of the unit is facilitated, and by rotating the lead holder 57 continuously circular points 20 may be produced, while flat or polygonal points may also be produced by lifting the holder 57 away from the rotor 11 and intermittently only partially rotating the same. All parts of the improved unit may be easily and accurately constructed and assembled at moderate cost to provide a durable and attractive assemblage which is readily attachable to a support 30, and the invention has proven highly satisfactory and successful in actual use. While this improved device is not an ordinary pencil sharpener, it has

extreme utility especially for draftsmen and illustrators who require utmost precision and accuracy in the formation and shaping of lead points confined within lead holders 57.

I claim:

1. In a shaper for pencil leads confined within a holder, a rotor having an annular lead reducing side surface generated by revolving a radial line disposed at an oblique angle relative to the rotor axis about said axis and also having an annular fillet surrounding said axis and merging with the inner edge of said surface, means for rapidly revolving said rotor about said axis, and a guide cooperable with said holder to direct each lead longitudinally and across said surface against said fillet, said guide having an abutment cooperable with the end of the holder to produce finished points of definite length and of predetermined shape each having a tip following the fillet contour and a taper receding from said tip and following the contour of said surface.
2. In a shaper for pencil leads confined within a holder, a rotor having an annular lead reducing side surface generated by revolving a radial line disposed at an oblique angle relative to the rotor axis about said axis and also having an annular fillet surrounding said axis and merging with the inner edge of said surface, means for rapidly revolving said rotor about said axis, and a guide cooperable with the holder to direct each lead longitudinally and radially with respect to the rotor axis across said surface against said fillet the bottom of said guide being cooperable with the inner end of the holder to produce finished points of definite length and of predetermined shape each having a tip following the fillet contour and a taper receding from said tip and following the contour of said surface.
3. In a shaper for pencil leads confined within a holder, a rotor having an annular lead reducing side surface generated by revolving a radial line disposed at an oblique angle relative to the rotor axis about said axis and also having an annular fillet surrounding said axis and merging with the inner edge of said surface, means for rapidly revolving said rotor about said axis, and a guide cooperable with the holder to direct each lead longitudinally and across said surface against said fillet, said guide having a bottom abutment cooperable with the inner end of the holder to positively arrest the inward travel of the lead to produce finished points of definite length and of predetermined shape each having a tip following the fillet contour and a taper receding from said tip and following the contour of said surface.
4. In a shaper for pencil leads confined within a holder, a rotor having an annular lead reducing side surface generated by revolving a radial line disposed at an oblique angle relative to the rotor axis about said axis and also having an annular fillet surrounding said axis and merging with the inner edge of said surface, means for rapidly revolving said rotor about said axis, a guide cooperable with said holder to direct each lead longitudinally and across said surface against said fillet to produce finished points of definite predetermined shape each having a tip following the fillet contour and a taper receding from said tip and following the contour of said surface, means associated with said guide for positively arresting the inward movement of the holder to produce points of definite length, and means for adjusting the position of said guide

relative to said rotor side surface to vary either the thickness or the taper or the predetermined length of the lead points.

5. In a shaper for pencil leads confined within a holder, a rotor having an annular lead reducing side surface generated by revolving a radial line disposed at an oblique angle relative to the rotor axis about said axis and merging directly in the outer edge of an annular reducing surface disposed perpendicular to said axis and the inner edge of which in turn merges directly with an annular fillet surrounding said axis, means for rapidly revolving said rotor about said axis, and a guide cooperable with the holder to direct each lead longitudinally and radially across said surfaces against said fillet to produce finished points of definite shape each having a tip following the fillet contour and successive cylindrical and tapered surfaces receding from said tip, and means associated with said guides for positively

arresting the inward movement of the holder at a definite locality.
